UNITED STATES PATENT OFFICE.

ANDREW KROUSE, OF BRIDGEPORT, CONNECTICUT.

DESIGN FOR A CANE-HANDLE.

SPECIFICATION forming part of Design No. 23,039, dated February 6, 1894.

Application filed December 28, 1893. Serial No. 495,011. Term of patent 3 $\frac{1}{4}$ years.

To all whom it may concern:

Be it known that I, ANDREW KROUSE, a citizen of the United States, residing at Bridgeport, in the county of Fairfield and State of Connecticut, have invented and produced a new and original Design for Cane-Handles; and I do hereby declare the following to be a full, clear, and exact description of the invention, such as will enable others skilled in the art to which it appertains to make and use the same.

In the accompanying drawings which illustrate my design Figures 1 and 2 are elevations of opposite sides of a cane handle showing my design.

The leading feature of my design consists in the foliate ornamentation which extends along the top, bottom and extremity of the handle, and also extends down the front and back portions of the shank of such handle, and the emblems and insignia appearing in raised lines along the opposite sides of the handle and shank and contained between the foliate ornamentation.

1 is the cane handle, 2 the shank thereof, 25 3 the foliate ornamentation along the top, bottom and extremity of such handle, and also extending down the front and back portions of the shank, and 4 are the emblems and insignia on opposite sides of the handle and shank and inclosed by the foliate ornamentation.

I claim—

The design for cane handles substantially as shown in the accompanying drawings. 35

In testimony whereof I affix my signature in presence of two witnesses.

ANDREW KROUSE.
